MULTIPLE CIRCUIT BREAKING DEVICE
FOR KNITTING MACHINES

Samuel Mishcon, Brooklyn, N. Y.

Application March 19, 1935, Serial No. 11,800

6 Claims. (Cl. 66—163)

This invention relates to a multiple circuit-breaking device, particularly of the type used in conjunction with a circular knitting machine for stopping the machine due to such conditions as a 5 broken thread, entanglement of the thread into a knot, excessive tension on the thread or the exhausting of the yarn on the spool,—one of the main objects of the invention being to present a relatively simple unitary device having the contacting elements completely encased in a single 10 dust-proof housing.

In the usual type of apparatus of this class known in the trade as electric stop-motion devices, there is a complete electric circuit-breaking 15 mechanism in each of a plurality of separate and independent boxes, one for each thread of yarn operatively engageable with the machine. These boxes contain an aperture therein to accommodate a lever during its operative movement, said 20 aperture being exposed to the atmosphere and hence constantly subject to the accumulation therein of dust and foreign particles which may seriously affect and impede the operation of the contacting elements. It is hence one of the 25 objects of my invention to overcome this disadvantage by housing the contacting elements in a single dust-proof casing, without in any way interfering with the operative engagement with the machine of each thread of exposed yarn.

30 In the old form of stop-motion device where separate boxes are employed, each box must contain as aforesaid, an independent circuit-breaking mechanism, making the device relatively intricate in structure. It is hence another object 35 of my invention to simplify the construction of devices of this class by employing circuit-breaking means containing a single unitary contact element and operable by each of the threads engageable with the machine.

40 Where a multiplicity of independent circuit-breaking boxes are employed, separate adjustments must be made for each box in accordance 45 with the tension requirements of the particular threads of yarn being used on the knitting machine. With the use of my invention, however, a simple manual manipulation will produce a simultaneous adjustment for a plurality of threads used in the machine, the accomplishment of which constitutes still another object of my invention.

50 Other features, advantages and objects will appear from the drawing and the description hereinafter given.

55 Referring to the drawings,

Figure 1 is a front elevation of a knitting ma-

chine provided with the multiple circuit-breaking device constituting my invention.

Figure 2 shows the relative positions of the yarn rest and yarn contact lever with a thread therebetween, as used in my invention,—the dot-dash 5 lines representing the position of the said lever when it is dropped due to the absence of a supporting thread.

Figure 3 shows the position of the yarn support 10 and yarn contact lever when the former is pulled down by a thread due to excessive tension.

Figure 4 is a fragmentary section of the yarn-controlled members at the outer extremity of a radial arm, showing the relative positions of the 15 yarn rest, the yarn contact lever, the shaft, the tubular arm and the tubular housing for the arm.

Figure 5 is a plan view of the casing and some 20 of the radial elements and associated parts constituting my invention.

Figure 6 is a vertical section taken along line 25 6—6 of Figure 5 and the supporting structure for the casing.

Figure 7 is a development of a fragmentary sectional view taken along line 7—7 of Figure 5, 30 showing various positions of the contact terminals 25 with respect to the unitary circular contact element with which they are engageable, and

Figure 8 represents another form of the yarn-actuated control members at the outer terminal 35 of a radial arm, showing the yarn contact lever 30 underlying the thread,—the dot-dash lines indicating the position of said lever during the absence of the thread.

In the drawings, the stationary framework 10 of a circular knitting machine is associated with 40 the rotary cylinder 11 which operatively receives a plurality of threads of yarn, such as those identified by the numerals 12 and 13, from a corresponding number of circumferentially disposed spools, such as 14 and 15,—various types of 45 threads being employed in predetermined relationship in accordance with the nature of the fabric to be knitted. Suitably mounted upon the framework 10 is the post 16 which supports the casing 17 of the multiple circuit-breaking device 45 18 containing the elements of my invention.

The threads of yarn, on their way to the cylinder, pass over pulleys 19 and are thereafter slidably pulled over the yarn rests 20 and rings 21 and 22 to be taken up by the needles circumferentially 50 disposed about the cylinder which is operatively rotated through the action of the belt 23, the clutch 24 and gear 25.

55 Peripherally disposed about the casing 17 are a plurality of yarn-controlled elements, each in-

cluding the conventional yarn rest 20 and yarn contact lever 26, operatively associated with a plurality of radial members the details of which will be more specifically described hereinafter. 5 Each of said yarn rests is fork-shaped, containing the two spaced supports 27 and 28, and is mounted over the outer terminal of one of the tubular radially disposed arms 29 and affixed thereto by the screw 30. The said arm 29 extends 10 into the lateral wall 31 of the casing 17, and is rotatably supported therein by the fixed tubular housing or support 33 which is secured to said lateral wall by the nuts 34 and 35. Contained within said arm 29 and extending therethrough is the 15 shaft 36, the outer terminal of which is joined to the lever 26 and the inner terminal provided with the contact terminal or switch element 37 suitably affixed thereto.

The casing 17 contains therein the circular contact-element or ring 38 mounted on insulating post 39,—the peripheral portion of said element underlying the said terminals 37 which are adapted for contacting engagement therewith. Electrically connected to the circular contact element 38 is the conductor 40, which is shown as consisting of several sections suitably joined together so as to enable it to be operatively applied to knitting machines of various dimensions,—said conductor being electrically connected to a suitable source of current supply through the conducting elements 41, 42 and 43.

Slidably engageable and circumferentially disposed with respect to the inner surface of the lateral wall 31 of the casing are the two cylindrical rings or sleeves 44 and 45, positioned at two different levels, each of said sleeves containing lugs 46 and 47 extending outwardly into the space 49 formed by the extended wall 50 of the casing 17. In threaded engagement with said wall 50 are the 40 screws 51 and 52 which extend into said space 49 for abutment against said lugs 46 and 47 respectively. Anchored at a plurality of points along the inner surface of said sleeves are the springs 53 and 54,—the former representing the springs 45 on the upper sleeve and the latter those on the lower sleeve. Each of these springs is also anchored to the fingers 55 attached to the inner extremities of each of the tubular arms 29, preferably in alternate arrangement with respect to the 50 upper and lower sleeves.

In the operation of this device, the action of the yarn-controlled members as shown in Figures 2 and 3 is well known to the art. The thread 12 is supported by the two supports 27 and 28 of the 55 yarn rest 20, and superimposed upon and supported by said thread is the yarn contact lever 26. Should the thread break, or should the yarn on the spool become exhausted, the lever 26, being no more supported by the thread 12, will, in this 60 form of device, drop down under the influence of gravity, thereby causing a rotary movement of the shaft 36 to downwardly carry with it the contact terminal 37 within the casing until contact is made with the circular contact element 38. When 65 this occurs, an electric circuit will be closed, said circuit extending from a source of current supply through the conductors 43, 42, 41, 40, the contact element 38, the terminal 37, the casing 17, and through a common ground connection to the 70 solenoid 56 (see Figure 1). Upon a closing of said circuit the core 57 of the solenoid is drawn to the right, permitting the spring 58 to actuate the member 59 upwardly and into operative engagement with the lever 60, thereby breaking the toggle of which arm 62 is a member and conse-

quently releasing the bar 61 from the locking position of the toggle arm 62. This permits the spring 63 to draw said bar 61 to the left and disengage the clutch 24 from the pulley operated by the belt 23. In this way, the gear 25 ceases to 5 actuate the cylinder 11 and the machine is brought to a stop, an event which is generally rendered more positive by the simultaneous action of a braking mechanism (not here shown). It is thus obvious that with the absence of a thread 10 such as 12 on any of the yarn rests, the terminals 37 will be brought into engagement with the unitary contact ring 38 to effect a stopping of the knitting operations. Instead of employing a plurality of independent circuit-breakers at the terminal portion of each radial arm, as is commonly the practice, this invention enables one unitary contact element 38 to coact with any one of the terminals 37 for the required purpose.

If for some reason the tension of the thread 12 20 should increase, or in the event of the entanglement of the thread into a knot, either this excessive tension or the pull of the knot will cause the yarn rest 20 to swing downwardly as is shown in Figure 3, against the action of a spring such as 25 53 anchored to the rotatable arm 29. Inasmuch as the lever 26 is still supported by the thread, and the thread by the yarn rest, the downward or clockwise movement of the yarn rest will cause the lever to similarly move downwardly, effecting a 30 contacting of the terminal 37 with the contact ring 38 to cause a stopping of the machine in the aforesaid manner.

By referring to Figure 7, it will be seen that the terminal 37a has dropped as a result of the absence of thread, inasmuch as the finger 55 is still in its upward position, indicating that the yarn rest has not moved from its original position. Terminal 37b however, which is also in engagement with the contact ring 38, has been 40 brought to that position by the downward movement of the yarn rest, due perhaps to an increase in tension of the thread, as is evident by the position of the finger 55a and the expanded condition of the spring 53a. After contact is made in 45 the last-referred-to manner, the spring returns the yarn rest 20 to its normal position by rotatably returning the finger 55a and the connected arm 29 to their original inoperative positions,—the return movement being limited by the stop 50 68 on the tubular housing 33.

Should it be desired to vary the tension in springs 53 and 54 in accordance with the tensile strength of the particular threads of yarn being used on the knitting machine, this can be readily 55 effected by manipulating the screws 51 and 52 against the lugs 46 and 47, thereby causing a rotary movement of the sleeves 44 and 45 to either separate the anchoring points of the springs and thereby increase the tension therein 60 or bring them together to decrease their tension. If two types of yarn, such as silk and wool, are simultaneously used in a knitting machine, one type can be operatively controlled by the springs on the sleeve 44 and the other by the springs on 65 sleeve 45. In this way it is unnecessary to make independent and separate adjustments for each spring and each thread of yarn, inasmuch as a simple manipulation of the screws 51 and 52 will simultaneously adjust the tension in all the 70 springs on one sleeve.

It should further be noted that inasmuch as all the contacting elements are contained within the casing 17, provided with cover plate 32, this apparatus is free from the danger of dust and 75

dirt accumulating therein to adversely affect the operation of the contacting elements. This is a decided advantage over the old form of circuit-breaking devices containing a plurality of separate and independent boxes generally exposed to the atmosphere with the resultant coating of the contacting elements with dust and other foreign particles.

The yarn contact lever 26 with its shaft 36 can together be considered or termed a yarn contact device having at its housing end the switch lever 37, while the yarn rest 20 with its tubular arm or shaft 29 may be referred to as a yarn rest device.

This device is adaptable not only to the usual form of yarn-controlled elements such as are shown in Figures 2 and 3, but also to the arrangement of Figure 8 where the yarn 65 is superimposed upon the yarn contact lever 66 interposed between the two spaced supports of the yarn rest 67. The lever 66 is urged upwardly by the action of a spring or balancing means against the tension in the yarn 65, the tension being sufficient to hold the lever down. Should the yarn 65 break, the lever 66 will move upwardly to actuate the equivalent of the shaft 36 to establish contact with the unitary circular contact element 38.

It is of course understood that the various embodiments above described and shown in the drawings are illustrative of my invention and not employed by way of limitation, inasmuch as numerous changes and modifications may be made within the scope of the appended claims without departing from the spirit of this invention.

What I claim is:

1. In a machine of the character described, a yarn control mechanism comprising a yarn rest device and a yarn contact device revolvable within said rest device, a housing and a support radially mounted in the wall of said housing, said support having rotatably mounted therein said rest device and said contact device, stop means electrically connected to said machine, an electric terminal in said housing, an electric switch element on the housing end of said contact device and within said stop means circuit and adapted to close the electric circuit through said terminal for the operation of the stop means upon the operative movement of said yarn contact device, a spring-controlled lever on the housing end of said rest device yieldably holding said latter device against movement, and movable means positioned on the lateral wall of said housing adapted to adjust the spring tension on said lever.

2. In a machine of the character described, a yarn control mechanism comprising a yarn rest device and a yarn contact device rotatable within said rest device, a housing and a support radially mounted in the wall of said housing, said support sustaining said rest device substantially throughout the length thereof, stop means electrically connected to said machine, an electric terminal in said housing, an electric switch element on the housing end of said contact device and within the stop means circuit and adapted to close the electric circuit through said terminal for the operation of said stop means upon the operative movement of said yarn contact device, a spring-controlled lever on the housing end of said rest device yieldably holding said latter against movement, and movable means positioned on the lateral wall of said housing adapted to adjust the spring tension on said lever.

3. In a machine of the character described, a plurality of yarn control mechanisms comprising

each a yarn rest device and a yarn contact device rotatable within said rest device, a housing and a plurality of supports secured to and extending radially from said housing, each support having operatively mounted thereupon said rest device and the corresponding contact device, a stop mechanism electrically connected with said machine, an electric terminal in said housing, an electric switch element on the housing end of each contact device and within the stop mechanism circuit and adapted to close the circuit through said terminal for the operation of said stop mechanism upon the operative movement of the corresponding yarn contact device, a spring-controlled lever on the housing end of each rest device yieldably holding said latter device against movement, and movable means positioned on the lateral wall of said housing adapted to adjust a predetermined number of said levers for one tension and other of said levers for a different tension.

4. In a machine of the character described, a plurality of yarn control mechanisms comprising each a yarn rest device and a yarn contact device rotatable within said rest device, a housing and a plurality of supports secured to and extending radially from said housing, each support having rotatably mounted thereon one of said rest devices and a corresponding contact device substantially along the entire length thereof, a stop mechanism electrically connected with said machine, an electric terminal in said housing and within the stop mechanism circuit, an electric switch element on the housing end of each contact device adapted to close the circuit through said terminal for the operation of said stop mechanism upon the corresponding movement of the yarn contact device, a spring-controlled lever on the housing end of each rest device yieldably holding said latter device against movement, and movable means positioned on the lateral wall of said housing adapted to adjust a group of said levers for one yarn tension and another group of said levers for a different yarn tension.

5. In a machine of the character described, a plurality of yarn control mechanisms comprising each a yarn rest device and a yarn contact device revolvable within said rest device, a housing and a plurality of supports secured to and extending radially from said housing, each support being adapted to rotatably and fully sustain a rest device with its contact device, an electrically operated stop mechanism to interrupt the operation of said machine, an electric terminal in said housing, an electric switch element on the housing end of each contact device adapted to close the circuit through said terminal for the operation of said stop mechanism, a spring-controlled lever on the housing end of each rest device to take up the tension of the yarn on the rest device, and movable means located on the lateral wall of said housing above and below said supports, said movable means being adapted to adjust a predetermined number of said levers for one yarn tension and another group of levers for a different tension.

6. In a mechanism of the character described, a plurality of yarn control mechanisms comprising each a yarn rest device and a yarn contact device revolvable within said rest device, a housing and a plurality of supports fastened to and extending radially from said housing, each support having rotatably mounted therein one of said rest devices substantially along the entire

length thereof, means to limit the rotary motion of said rest devices, a stop mechanism electrically connected with said machine, a circular electrical terminal in said housing, an electric switch element on the housing end of each contact device and contained within the stop mechanism circuit and adapted to close the circuit through said terminal for the operation of said stop mechanism, a spring-controlled lever on the housing end of each rest device yieldably holding said latter device against movement, each

rest device being operatively connected with the corresponding contact device to operatively actuate the switch element thereof when the yarn rests under abnormal tension, and movable means positioned on the lateral wall and within said housing and above and below said supports, said movable means being adapted to adjust a predetermined number of said levers for one yarn tension and other of said levers for a different tension.

SAMUEL MISHCON. 10
